UNITED STATES PATENT OFFICE.

WALTER D. KAHN, OF CEDARHURST, NEW YORK, ASSIGNOR, BY MESNE ASSIGNMENTS, TO DIAMOND ELECTRIC SPECIALTIES CORP., OF NEWARK, NEW JERSEY, A CORPORATION OF NEW JERSEY.

PORTABLE LAMP.

Application filed February 27, 1919. Serial No. 279,627.

To all whom it may concern:

Be it known that I, WALTER D. KAHN, a citizen of the United States, and a resident of Cedarhurst, Nassau County, State of New York, have invented an Improvement in Portable Lamps, of which the following is a specification.

The present invention relates to an improvement in portable lamps, one object 10 being to provide a device of this character in which the electric lamp may be protected from injury by impact of the battery against the nipple end of said lamp. It is also contemplated that the present improvements will be instrumental in simplifying 15 and re-inforcing the construction of devices to which they may be applied.

An embodiment of my invention is illustrated in the drawings forming a part of the 20 present specification and in which,

Figure 1 is an elevation,

Figure 2, a central vertical section,

Figure 3, an enlarged detail view partly 25 in section of the switch mechanism,

Figure 4, a vertical section of a portion 30 of the device to show the construction of the buffer and re-inforcing means applied to a casing of non-conductive material,

Figure 5, a plan view of a portion of said 35 buffer, and

Figure 6, a modification of the assembly 40 of the buffer in a casing made of metal or other conductive material.

As shown in the drawings, a device embodying my invention may include a casing 45 1 of any suitable material, either conductive or a non-conductive. At one end of said casing, a cap 2 may be attached by any suitable means, here shown as a threaded portion 50 engaging a similarly threaded portion of the casing. Said cap is preferably provided with a spring member 3 adapted to bear against a battery 4 having one pole at 5 and the other pole at 6. At the end of the 55 casing opposite cap 2, is another similarly attached cap 7 provided with an opening adapted to receive and retain a lens or other light transmitting member 8.

Between the lens 8 and battery 4, I provide 60 lamp supporting means and means adapted to facilitate contact between one pole of the lamp and pole 5 of the battery. I also provide means for establishing contact between the opposite pole of the lamp and pole 6 of the battery. For this purpose, a

metallic strip 9 is secured to the casing in such a manner that one end of said strip will be in contact with a portion of cap 2 which in turn is in current conducting relation to pole 6 of the battery through the 60 spring 3. Another strip 10 is also secured to the casing 1, said strips 9 and 10 being connected and disconnected electrically by means of a suitable switch here illustrated as including terminals 11 and 12, adapted 65 to contact with corresponding terminals on the strips 9 and 10.

In the present embodiment of my invention, a lamp 13 may be supported by a reflector 14 having a threaded socket portion 70 15 adapted to receive the nipple 16 of said lamp. As illustrated in Figs. 4, 5 and 6, a buffer 17 may be rigidly secured to the casing 1 by any suitable means, here shown as upset eyelets 18 passing through said casing 75 and through corresponding openings in straps 19 attached to or forming a part of the buffer 17. A projecting contact member 21 may be provided to engage the pole of the lamp 13 to transmit the current passing 80 between said lamp and pole 5 of the battery.

In operation, the battery 4 may be inserted in the casing 1 in the usual manner, whereupon pole 5 will engage contact 20. 85 By securing cap 2 to the lower end of the casing 1, the battery will be held in spring-pressed engagement with said contact 20 and also with the metallic portion of said cap 2. The circuit between the battery and the lamp 90 may be closed by manipulating the switch mechanism, as will be readily understood. It is contemplated that the buffer 17 may serve to relieve the lamp from impact of the battery, both when the latter is being inserted 95 in the casing and also when the lamp is being carried and subjected to severe handling. Thus, the interposing of a rigid member between pole 5 of the battery and the corresponding pole of the lamp will prevent the latter from being crushed in by weight of the battery. Also, a rigid member inserted in the casing will be effective in re-inforcing 100 said casing, particularly where the latter is made of fibrous material common in the art. 105

I claim as my invention:

1. In a portable electric light, the combination of a casing, a battery within the casing, a lamp in circuit with said battery and a buffer extending across the casing and 110

rigidly attached thereto and having a resilient contact member in constant yielding engagement with the lamp.

2. In a portable electric light, the combination of a casing, a battery within the casing, a lamp in circuit with the battery, and a U-shaped metallic strap secured to the casing and arranged between the lamp and the battery and having a resilient contact member in constant yielding engagement with the lamp.

3. In a portable electric light, the combination of a casing, a metallic buffer in the form of a strap extending across the casing and attached to opposite walls thereof and a resilient contact member mounted upon the buffer.

4. In a portable electric light, the combination of a cylindrical casing of insulating material, a metallic U-shaped strap extending across the casing and attached thereto,

a lamp and a resilient contact member in constant yielding engagement with the lamp, comprising a strip of metal folded upon itself, mounted upon the strap adjacent the central portion thereof.

5. In a portable electric light, the combination of a casing, a battery within the casing, a lamp in circuit with the battery, a metallic buffer extending across the casing and rigidly connected thereto and provided with a depression adjacent its central portion, constituting a contact for engagement with one pole of the battery and a resilient contact in constant yielding engagement with the lamp, mounted upon said buffer adjacent its central portion.

In testimony whereof, I have signed my name to this specification this 25th day of February, 1919.

WALTER D. KAHN.
